The ornamental design for a display screen with a graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a first embodiment of a display screen with a graphical user interface showing our new design;

FIG. 2 is a front view of a second embodiment of a display screen with a graphical user interface showing our new design; and,

FIG. 3 is a front view of a third embodiment of a display screen with a graphical user interface showing our new design.

The broken lines shown in FIG. 1 illustrate portions of the display screen with a graphical user interface that form no part of the claimed design.

The outer edge of the display screen is understood to be congruent with the outer edge of the graphical user interface.
